FLUORESCENT LAMP STARTER

Charles H. Hodgkins, Fairfield, Conn., assignor to
 The Bryant Electric Company, Bridgeport,
 Conn., a corporation of Connecticut

Application March 4, 1942, Serial No. 433,301

5 Claims. (Cl. 200—122)

The present invention relates to starting relays for fluorescent lamps and particularly to a thermal relay which automatically operates to start such lamps, and, if for any reason the lamp fails to start after a predetermined period of time, the relay likewise operates to disconnect the failed lamp from the source of supply and is automatically reset upon replacement of the failed lamp.

A relay of this type is shown and claimed in my copending application, Serial No. 430,887, filed February 14, 1942, which operates in the above mentioned manner, except that such relay required that it be manually reset upon replacement of a failed lamp. Under certain conditions, such for example as when a lamp and relay are part of a fixture secured to a comparatively high ceiling, this manual resetting of the relay is a distinct disadvantage. In order to operate relays of this type, the heat-responsive element is heated by an electrical resistance heater which must rapidly heat the heat-responsive element to cause operation of the latter with attendant initiation of a discharge in the lamp; and once the lamp has started, such heater must generate just sufficient heat to maintain the heat-responsive element in a predetermined position. This accordingly imposes rather critical resistance characteristics upon the heater element, which is a further disadvantage from the standpoint of mass production of relays, since each resistance heater must be accurately tested and only those within narrow tolerance limits accepted for use.

It is accordingly an object of the present invention to provide a thermal relay for the starting of fluorescent lamps which automatically operates to disconnect a failed lamp from the source and wherein the relay also automatically resets upon replacement of the failed lamp.

Another object of the present invention is the provision of a thermal relay for starting fluorescent lamps which performs a sequential operation to start the lamp and, if for any reason the lamp has failed, the relay automatically performs a predetermined number of repetitive operations corresponding to a predetermined period of time, after which it automatically operates to disconnect the failed lamp from the source and is automatically reset upon replacement of the defective lamp.

Another object of the present invention is the provision of a thermal relay for starting fluorescent lamps wherein a resistance heater of low ohmic value is employed to initially operate the relay, and a second resistance heater of high

ohmic value is utilized to maintain the relay in a predetermined position, thus eliminating the necessity for a heater element having narrow resistance characteristics.

5 A further object of the present invention is the provision of a thermal relay for starting fluorescent lamps which operates with fidelity to perform a sequential operation, including disconnection of the lamp from the source of supply in the event of lamp failure, and which automatically resets itself upon replacement of the defective lamp.

Still further objects of the present invention will become obvious to those skilled in the art by reference to the accompanying drawings wherein:

Fig. 1 is a sectional view of the starting relay unit of the present invention and showing a front elevational view of the relay itself;

Fig. 2 is a fragmentary sectional view of the relay of Fig. 1 taken at 90° to the latter and showing the normal open position of the relay prior to its operating;

Fig. 3 is a sectional view taken on the line III—III of Fig. 1;

Fig. 4 is a sectional view taken on the line IV—IV of Fig. 1 and showing the closed circuit position of the relay;

Fig. 5 is a sectional view identical to Fig. 4 but showing the relay in its normally open position during operation of the lamp;

Fig. 6 is a sectional view identical to Fig. 4 but showing the position of the relay in the "lock-out" position which the relay assumes upon failure of the lamp to start after a predetermined number of repetitive operations of the relay corresponding to a predetermined period of time;

Fig. 7 is a schematic diagram of the circuit for starting a fluorescent lamp and utilizing the thermal relay of the present invention;

Fig. 8 is a sectional view of a starting relay unit showing in front elevation a modification which the thermal relay of the present invention may take;

45 Fig. 9 is a fragmentary sectional view of the relay as shown in Fig. 8, taken at 90° to the latter and showing the normal position of the relay prior to energization of the discharge lamp;

Fig. 10 is a sectional view taken on the line X—X of Fig. 8;

Fig. 11 is a sectional view taken on the line XI—XI of Fig. 8;

Fig. 12 is a sectional view taken on the line XII—XII of Fig. 8 and showing the closed circuit position of the relay;

Fig. 13 is a sectional view identical to Fig. 12 but showing the position of the relay during operation of the lamp;

Fig. 14 is also a sectional view identical to Fig. 12 but showing the "lock-out" position which this particular modification of the present invention takes upon failure of the discharge lamp due to deactivation of the electrodes, and

Fig. 15 is a schematic diagram similar to Fig. 7 but showing the circuit arrangement for starting a fluorescent lamp utilizing the modification of the starting relay as shown in Figs. 8 to 14.

Referring now to the drawings in detail, the starting relay of the present invention is shown generally at 5 in the several figures, and is housed within a metallic or plastic casing 6, together with a radio-frequency-suppressing condenser 7, both of which are connected in electrical parallel to a pair of socket terminals 8 and 9 adapted to engage a socket and which are secured to an insulating closure member 10.

The relay itself comprises a base 12 of suitable insulating material such as fiber, a phenolic condensation product, hard rubber or the like, and, as shown in Fig. 1, this base is provided with an elongated opening 13 for a purpose hereinafter described. A heat-responsive element in the form of a bimetallic member 14 is secured at one end to the back of the base 12 and is angularly bent to extend through the opening 13 and form a corrugation therein with its free end depending in the opening 13 and provided with a contact terminal 15.

As can be more clearly seen from Figs. 2, 4, 5, and 6, a second heat-responsive element or bimetallic member 16 of substantially the same configuration as the bimetallic member 14, is secured at one end to the front of the base 12 and substantially parallels the bimetallic member 14 in every respect, being also provided with a contact terminal 17 adjacent the contact terminal 15, which thus normally positions the heat-responsive elements 14 and 16, together with their respective contacts 15 and 17, in spaced relation to each other. Moreover, since both heat-responsive elements are bimetallic and deflect in the same direction, the spacing therebetween remains constant with changes in ambient temperature. An electric resistance heater element 18 of relatively high ohmic value is mounted on the base 12, under the corrugation formed in the bimetallic member 14, by means of a pair of rod-like conductors 19 and 20 which extend to the respective socket terminals 8 and 9. In addition, the conductor 19 is soldered or otherwise affixed to an eyelet or the like 22, the latter of which extends through the base 12 and is connected by a conductor 23 (Figs. 3 and 7) to one side of the condenser 7. This eyelet 22 is also rigidly secured to a metallic strip 24 disposed horizontally on the front face of the base 12 to which the heat-responsive element 16 is likewise connected, thus connecting one side of the heater 18, one side of the condenser 7 and the heat-responsive element 16 together, as shown more clearly in Fig. 7.

In a similar manner the conductor 20 is soldered or otherwise affixed to an eyelet 25 likewise extending through the base 12 and connected by a conductor 26 to the other side of the condenser 7, as well as to a metallic strip 27 horizontally disposed on the back of the base 12 and to the heat-responsive element 14. Thus by reference to Fig. 7 it will be noted that the heater, condenser and heat-responsive elements 14 and

16 are connected in electrical parallel with each other and to the socket terminals 8 and 9. When the relay unit is inserted in a socket, the heater 18 is accordingly connected in a series circuit comprising an inductance element 28 and the filamentary electrodes 29 and 30 of the discharge lamp 32.

Upon closure of a switch 33, the full voltage of the source of supply L₁—L₂, which may be a transformer or preferably a commercial source of potential of 115 volts and which will be hereinafter referred to as full line voltage, is impressed across the heater 18 through lamp electrodes 29 and 30. The heater 18 heats the heat-responsive element 14 very quickly, causing it to deflect so that the contact 15 carried thereby engages the contact 17 carried by the heat-responsive element 16, as shown in Fig. 4. This engagement of the contacts 15 and 17 accordingly short-circuits the heater 18, forming a low resistance path in parallel with the latter and constituting a series heating circuit for the lamp electrodes 29 and 30, which thus rapidly heats the latter to maximum electron emitting temperature during the time the contacts 15 and 17 remain closed.

The heater 18 thus ceases to develop heat, with the result that the heat-responsive element 14 cools and returns toward its normal position, thus interrupting engagement of the contacts 15 and 17, as shown in Fig. 5. Upon separation of the contacts 15 and 17, a high voltage surge is impressed by the inductance 28 across the preheated lamp electrodes 29 and 30, which initiates a discharge in the lamp 32. During operation of the lamp 32, the heater 18 is subjected only to lamp voltage and at such voltage insufficient heat is developed to again cause deflection of the heat-responsive element 14 to the extent that the contacts 15 and 17 engage each other, with the result that the relay 5 remains in the open position as shown in Fig. 5 during operation of the lamp 32.

If for any reason the discharge is not initiated in the lamp 32 upon initial operation of the relay 5, the latter will immediately repeat its cycle of operation, since the heater 18 will again be subjected to substantially full line voltage and such repetitive operation will continue until the lamp finally starts. Should, however, the lamp 32 have failed, due to deactivation of the electrodes or similar cause, the relay 5 will continue its cycle of operation only for a predetermined number of operations corresponding to a predetermined period of time, after which the relay then operates to "lock-out" the defective lamp.

Inasmuch as the heater 18 is, as above noted, immediately subjected to substantially full line voltage upon separation of the contacts 15 and 17 in the event the lamp fails to start, the heat developed by the heater 18 at this full line voltage is very shortly transmitted not only to the heat-responsive element 14, but also to the heat-responsive element or bimetallic member 16. As a consequence, this latter member 16 will deflect away from the base 12 at the same time that the heat-responsive element 14 deflects in the same direction in its normal operation in an endeavor to close the contacts 15 and 17.

Inasmuch as the heat-responsive element 14 is in closer proximity to the heater 18, there is naturally more of a time lag in the transfer of heat to the heat-responsive element 16, which in the absence of provisions to the contrary would even-

tually result in the element 14 overtaking the element 16 with closure of the contacts 15 and 17 and further useless repetitious operation of the relay 5 in a futile attempt to start the defective lamp 32. To prevent this, a stop 34 is secured by an eyelet or the like 36 to the base 12. As shown in the several figures, this stop 34 is provided with a detent projecting into an opening in the base 12 to prevent rotation about the pivot formed by the eyelet 36, and its opposite end is bent angularly outward from the base 12 and projects upwardly beyond the arc which the end of the heat-responsive element 14 would traverse.

Consequently, with repetitious operation of the relay for a predetermined number of times corresponding to a predetermined period of time and attendant deflection of the heat-responsive elements 14 and 16 in the manner above stated, the heat-responsive element 14 engages the stop 34, as shown in Fig. 6, which thus prevents its contact 15 from engaging the contact 17 carried by the heat-responsive element 16 and short-circuiting the heater 18. The latter accordingly continues to receive full line voltage, maintaining the defective lamp 32 in a "locked-out" condition, thereby preventing futile operation of the relay and annoying flickering of the lamp. When the defective lamp is replaced, the circuit is naturally broken, causing the relay 5 to automatically assume its normal position, as shown in Fig. 2, due to cooling of the heat-responsive elements 14 and 16, thus placing such relay again in condition for its customary cyclic operation.

It will thus be seen from the foregoing that a thermal relay for starting fluorescent lamps is herein provided which is simple in operation and economical to manufacture. The relay is provided with normally open contacts which are closed to initially connect the lamp to a source of supply, with closure of such contacts being controlled by a resistance heater. Inasmuch as such heater must not develop sufficient heat to cause closure of the contacts during operation of the lamp, its resistance characteristics must be confined to rather restricted limitations. Under certain conditions it may also be desirable to provide the thermal relay with normally closed contacts so as to decrease the time lag between closure of the switch and starting of the lamp.

The present invention also contemplates a relay of this latter type, and such modification is shown in Figs. 8 to 15, inclusive. The relay shown generally at 55 is housed within the casing 56, together with the condenser 57, and socket terminals 58 and 59 are carried by the closure member 60 in the same manner as previously described. The base member 62 is also provided with an opening 63 for the same purpose as in the previously described embodiment. A heat-responsive element in the form of a bimetallic member 64 and practically identical to the element 14 in Fig. 1 is likewise secured at one end to the back of the base 62, which depends downwardly in the opening 63 and is provided with a contact 65 at its lower end.

As shown more particularly in Fig. 9, this contact 65 normally engages a contact 66, the latter of which is carried by a bimetallic stationary contact arm 67 extending angularly in the opening 63 and secured at one end by means of a rivet or the like 68 to the base 62. Another bimetallic stationary contact arm 69 is secured to a bracket 70, the latter of which is provided with an angularly disposed portion so as to position the an-

chored end of the bimetallic contact arm 69 in spaced relation to the base member 62. This bimetallic arm 69 is provided with a contact terminal 72 at its free end and disposed in juxtaposition to the contact terminal 65 carried by the bimetallic element 64. As in the previously described embodiment, a heater element shown generally at 73 is disposed in the corrugation formed in the bimetallic element 64. This heater element, however, differs somewhat from that previously described in that it is formed by two resistance heater elements, as shown more particularly in the schematic diagram of Fig. 15.

By reference to this latter figure, it will be noted that one such resistance heater 74 is of relatively low ohmic value, whereas the inner surrounded resistance heater element 75 is of relatively high ohmic value. One end of both resistance heaters 74 and 75 is connected by a conductor 76 to the socket terminal 58. This conductor 76 is also soldered or otherwise affixed to an eyelet or the like 77 passing through the base 62 and through the bracket 70, which thus connects the bimetallic member 69 with one end of each of the electric resistance heaters 74 and 75, as well as to the socket terminal 58. The opposite end of the heater 74 is connected by a conductor 78 to the bimetallic stationary contact arm 67, while a conductor 79 connects the remaining end of the high resistance heater element 75 to the socket terminal 59. An eyelet 80 extending through the base 62 is soldered or otherwise secured to this conductor 79, and the bimetallic element 64 is connected by this eyelet 80 to the heater element and socket terminal. The condenser 57 is connected by conductors 82 and 83 to the eyelets 77 and 80, which thus connects the condenser 57 in parallel with the high resistance heater element 75 across the socket terminals 58 and 59.

By reference now more particularly to Fig. 9, will be noted that in the open circuit position of the switch 33, in the relay of this particular modification the contact terminals 65 and 66 are normally in engagement with each other. Inasmuch as both such contacts are carried by the bimetallic elements 64 and 67, respectively, changes in ambient temperature are thereby compensated so that under all ambient temperature conditions the contacts 65 and 66 remain in engagement with each other. Upon closure of the switch 33 as shown in Fig. 15, the cathodes 29 and 30 of the lamp 32 are supplied with substantially full line voltage through a circuit which extends from one side of the line L1 through inductance 28 to the filamentary cathode 29, and thence to the socket terminal 58 through conductor 76, low resistance heater element 74, conductor 78, thence through normally closed contacts 66, 65, carried respectively by the bimetallic elements 67, 64, to socket terminal 59 and thence through filamentary electrode 30, back through switch 33 to the opposite side of the line L2. Resistance heater 74 being of relatively low ohmic value quickly generates heat, which causes bimetallic member 64 to deflect away from stationary bimetallic contact arm 67, thereby interrupting the series heating circuit for the filamentary lamp electrodes 29, 30. The time required to heat the heater element 74 prior to deflection of the bimetallic member 64 is sufficient to preheat the filamentary electrodes 29, 30 to maximum electron emitting temperature.

Upon separation of the contact terminals 65, 66 a high voltage surge is produced by the in-

ductance element 28 in the same manner as previously described, with the result that a discharge is initiated in the lamp 32 between the preheated electrodes. Opening of the contacts 65, 66 also interrupts the flow of current to the low resistance heater 74 and at the same time removes the substantially short-circuit condition previously existing with respect to the high resistance element 75, so that this latter is now in circuit during operation of the lamp 32 and is thus subjected to lamp voltage which is of a lower order of magnitude than line voltage to which the heater element 74 was previously subjected. At lamp voltage sufficient heat is generated by the high resistance heater 75 which is transmitted to the bimetallic member 64 to maintain the latter in an open circuit relationship with respect to bimetallic contact arm 67, so that the relay contacts assume the position as shown in Fig. 13.

Should, however, the lamp 32 fail to start on the first separation of the contacts 65, 66, the high resistance element 75 will immediately be subjected to line voltage and the resultant heat generated thereby will cause movable bimetallic member 64 to deflect still further away from the base 62 until it engages stationary contact arm 69, as shown in Fig. 12. This will establish a series heating circuit for the filamentary lamp electrodes 29 and 30 directly from the socket terminal 58, through conductor 76 to the bimetallic member 69 and the contact terminal 72 carried thereby, to the contact terminal 65 carried by the bimetallic member 64, and thence by means of conductor 79 to the other socket terminal 59, thus again completing the series heating circuit for the filamentary electrodes 29 and 30.

Engagement of the contact terminals 65, 72 short-circuits the high resistance heater 75, and since the contacts 65, 66 are open so that no current is received by the low resistance heater 74, no heat is generated, and movable bimetallic member 64 will cool and begin to restore itself to its normal position. The series heating circuit for the filamentary lamp electrodes 29, 30 will therefore be again interrupted and a high voltage surge from the inductance element 28 again impressed upon the preheated electrodes, thus initiating the discharge in the lamp 32. When the lamp starts, high resistance heater element 75 will then be subjected to lamp voltage and will generate sufficient heat to maintain movable bimetallic contact member 64 in the open circuit position between the two stationary contact arms 67 and 69, as shown in Fig. 13.

In order to cause the relay 55 to "lock-out" the lamp in the event the latter has failed due to deactivation of the electrodes or similar cause, as hereinbefore described, this modification is likewise provided with a stop 84 which is likewise carried by the base 62 and is bent so as to be engaged by the contact 85 carried by the movable bimetallic member 64. For example, if the lamp 32 fails to start after a predetermined number of repetitious operations of the relay 55 corresponding to a predetermined period of time, the high resistance heater 75 will be subjected to line voltage between each attempted operation of the relay 55 and there will be an increasing rise in temperature developed. This increased temperature will cause movable bimetallic member 64 to deflect further away from the base 62. The location of stationary bimetallic contact arm 69 is such that it is also influenced by the generated heat and, being bimetallic, will also move away from the base 62.

As a consequence, movable bimetallic contact member 64 will continue to deflect along with stationary bimetallic contact arm 69 away from the base 62 until the contact terminal 85 carried by the movable bimetallic member 64 engages the stop 84. Further deflection of the bimetallic member 64 is thus restrained, but stationary bimetallic contact arm 69 is free to continue its deflection away from the base so that it remains beyond a contact making position with the now restrained movable bimetallic member 64, with the relay assuming the position as shown in Fig. 14. The high resistance heater 75 is then continuously subjected to line voltage, and this open circuit condition for the lamp 32 is maintained. Moreover, further repetitious operation of the relay 55 is prevented as well as flickering of the failed lamp 32. When, however, the defective lamp 32 is replaced, both bimetallic members 64 and 69 cool and return to their normal position, as shown in Fig. 9, ready for initial operation to start the replaced lamp 32 in the manner as above noted.

Accordingly, by providing this modification with two electrical resistance heaters, one of low ohmic value and the other of high ohmic value, it is unnecessary that the range of resistance characteristics of the heaters be as limited as in the case of the single resistance heater element 18, as shown in the previously described embodiment, which accordingly prolongs the useful life of the two resistance heater elements in comparison with that of the single heater element shown in the relay of Fig. 1.

It thus becomes obvious to those skilled in the art that a starting relay for a fluorescent lamp is herein provided which operates with fidelity to start the lamp. Moreover, such relay performs its repetitious operation until a discharge is ultimately initiated in the lamp. If, however, the lamp is defective, such relay automatically operates to "lock-out" the failed lamp so as to prevent needless repetitious operation of the relay in a futile attempt to start a defective lamp; and upon replacement of such defective lamp, the relay automatically returns to its normal position preparatory to performing its normal cyclic operation to start the lamp.

In addition, the necessity for a heater element having resistance characteristics within a very narrow range may be eliminated, as in the present invention, by the provision of separate heater elements, one having a relatively low ohmic value for quick heating of the relay for starting purposes, and the other heater being of relatively high ohmic value so as to generate just sufficient heat to maintain the relay in a predetermined position during operation of the lamp.

Although several embodiments of the present invention have been shown and described, it is to be understood that many other modifications thereof may be made without departing from the spirit and scope of the appended claims.

I claim:

1. A relay for starting an electric discharge lamp comprising a base, heat-responsive means carried by said base in parallel spaced relation thereto, an electric heater disposed in heat transfer relation to said heat-responsive means for causing deflection of the latter upon the accumulation of heat therein, circuit-controlling means including a bimetallic element disposed in substantially parallel superimposed position relative to said heat-responsive means and operable to control a circuit to said lamp in response to nor-

mal deflection of said heat-responsive means due to heating and cooling of the latter, and means disposed in the path of deflected movement of said heat-responsive means and engageable by the latter upon the application of substantially full line voltage to said heater for a predetermined period of time to restrain said heat-responsive means from deflecting sufficiently to operate said circuit-controlling means.

2. A relay for starting an electric discharge lamp comprising a base, heat-responsive means carried by said base in parallel spaced relation thereto, an electric heater disposed beneath said heat-responsive means for causing deflection of the latter upon the accumulation of heat therein, circuit-controlling means including a bimetallic element disposed in substantially parallel superimposed position relative to said heat-responsive means for heating by said electric heater, and operable to control a circuit to said lamp in response to normal deflection of said heat-responsive means due to heating and cooling of the latter; and a stop carried by said base and projecting into the path of deflected movement of said heat-responsive means and engageable by the latter upon the application of substantially full line voltage to said heater for a predetermined period of time to restrain said heat-responsive means from deflecting sufficiently to operate said circuit-controlling means.

3. A relay for starting an electric discharge lamp comprising a base, heat-responsive means carried by said base in parallel spaced relation thereto and provided with a contact, an electric heater disposed in heat-transfer relation to said heat-responsive means for causing deflection of the latter upon the accumulation of heat therein, a normally stationary bimetallic member disposed in substantially parallel superimposed position relative to said heat-responsive means and provided with a contact adjacent the contact carried by said heat-responsive means and operable to deflect in the same direction as said heat-responsive means upon the application of a potential to said heater for a predetermined period of time, said contacts being operable to control a circuit to said discharge lamp in response to normal deflection of said heat-responsive means due to heating and cooling of the latter, and means disposed in the path of deflected movement of said heat-responsive means and engageable by the latter upon the application of substantially full line voltage to said heater for a predetermined period of time to restrain said heat-responsive means from deflecting sufficiently to cause its contact to engage the contact carried by said normally stationary bimetallic member and completing a circuit to said lamp when said bimetallic member is in a deflected position due to the accumulation of heat therein from said heater.

4. A relay for starting an electric discharge lamp comprising a base, heat-responsive means carried by said base in parallel spaced relation thereto, a comparatively low resistance electric heater in heat-transfer relation to said heat-responsive means for causing rapid deflection of

the latter upon the application of substantially line voltage to said low resistance heater, a pair of contacts normally completing a circuit to said lamp and to said low resistance heater and operable to interrupt said circuit upon deflection of said heat-responsive means, a comparatively high resistance heater element also in heat-transfer relation to said heat-responsive means and subjected to lamp voltage upon interruption of the circuit to said low resistance heater and normally operable to maintain said heat-responsive means in a deflected position to prevent said contacts from again completing a circuit to said low resistance heater during operation of said lamp, and a stop carried by said base and disposed in the path of deflected movement of said heat-responsive means to restrain deflection of the latter and prevent re-establishment of a circuit to said lamp and to said low resistance heater upon the application of substantially line voltage to said high resistance heater for a predetermined period of time.

5. A relay for starting an electric discharge lamp comprising a base, heat-responsive means carried by said base in parallel spaced relation thereto, a comparatively low resistance electric heater in heat-transfer relation to said heat-responsive means for causing rapid deflection of the latter upon the application of substantially line voltage to said low resistance heater, a pair of normally engaged contacts completing a circuit to said lamp and to said low resistance heater and operable to interrupt said circuit upon deflection of said heat-responsive means, a bimetallic element carried by said base in substantially parallel superimposed relation with respect to said heat-responsive means and provided with a contact normally disposed in spaced relation with one of said pair of contacts and operable to deflect in the same direction when heated as said heat-responsive means, a comparatively high resistance electric heater connected to the contact carried by said bimetallic element and in heat-transfer relation with said heat-responsive means and subjected to lamp voltage upon separation of said pair of contacts for maintaining said heat-responsive means in a predetermined position during operation of said lamp, said high resistance heater being operable to heat said heat-responsive means and cause engagement of one of said pair of contacts with the contact carried by said bimetallic element upon the application of substantially line voltage thereto due to failure of said lamp to start to cause repetitious operation of said relay until a discharge is initiated in said lamp, and a stop carried by said base and disposed in the path of deflected movement of said heat-responsive means to restrain deflection of the latter and prevent engagement of one of said pair of contacts with the contact carried by said bimetallic member when the latter is in a deflected position due to heating by said high resistance heater by the application of substantially line voltage to the latter for a predetermined period of time.

CHARLES H. HODGKINS.
